(57) **CLAIM**

The ornamental design for a phone, as shown and described.

DESCRIPTION

FIG. 1 is a top, front, right perspective view of a phone showing the new design;

FIG. 2 is a bottom, front, left perspective view thereof;

FIG. 3 is a bottom, rear, right perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged rear elevation view of a section indicated in FIG. 5.

The even length broken lines immediately adjacent the shaded areas represent the bounds of the claimed design while all other even length broken lines are directed to environment and are for illustrative purposes only; the broken lines form no part of the claimed design. The dot-dash broken line showing of the encircled portion in FIGS. 5 and 10 form no part of the claimed design. The logo trademark forming part of the disclosure n is a registered trademark of Caterpillar Inc.

1 Claim, 10 Drawing Sheets
